JAMES FRANK KEY, OF WASHINGTON, DISTRICT OF COLUMBIA.

TELLTALE FOR ELECTRIC LIGHTS.

996,489.

Specification of Letters Patent. Patented June 27, 1911.

Application filed December 30, 1908. Serial No. 469,959.

To all whom it may concern:

Be it known that I, JAMES FRANK KEY, a citizen of the United States, and resident of Washington, in the District of Columbia, 5 have invented certain new and useful Improvements in Telltales for Electric Lights, of which the following is a specification.

This invention relates to a device for indicating the operative condition of an electric light.

The object of the invention is to produce an arrangement for use in connection with ships' running lights, or other lights of which the continuous operation is important, 15 the arrangement being such that any failure of such lights, whether due to lack of current or to internal causes in the lamps or in their circuits, shall be disclosed with certainty by means of devices distant from such 20 lamps.

The invention consists in the use, for the purpose before described, of telltale-lamps, these telltale-lamps being arranged in shunt with the primary lamps of which they are to 25 indicate the condition, and having such resistance that, during normal operation, they glow dimly. In the case of a failure of current the telltale-lamps are extinguished, while in the case of failure in the primary 30 lamps, due to breakage or burning out or similar causes, the telltale-lamps glow brightly. In either case the failure of the primary lamps is indicated.

In the drawings: Figure 1 is a diagrammatic plan view of a ship having running lights and telltale-lamps arranged in accordance with the present invention; Fig. 2 is a diagram of the wiring connections of the arrangement shown in Fig. 1; and Fig. 3 is 40 a diagram of another method of connecting the lamps.

As shown in Fig. 1, the running lamps on the vessel 1 comprise a masthead light 2, a stern light 3, a port side-light 4, and a starboard side-light 5. The telltale-lamps corresponding to these running lights are located for convenience upon the bridge of the vessel, and are designated as 10, 9, 7 and 8, respectively.

50 As shown in Fig. 2, the running lights 2 and 3 are connected in series with each other and with a source of current 11, which may be a dynamo or other suitable source, the circuit passing from the dynamo, through a wire 22, to a lamp 2, thence, through a wire 14, to the lamp 3, and thence, through wires

16 and 23, back to the dynamo. The running lights 4 and 5 are also connected in series with each other in a branch circuit in multiple with the circuit through the lamps 2 and 3. This branch circuit passes from the wire 23, through a wire 24, to the lamps 4 and 5, and back from the latter, through a wire 25, to the wire 22, and thus to the dynamo.

Bridging each primary light is a shunt circuit including the corresponding telltale-lamp. Thus the telltale-lamp 10 is included in a shunt circuit 15 around the light 2, the telltale-lamp 9 is included in a shunt circuit 17 around the light 3, the telltale-lamp 7 is in a shunt circuit 19 around the lamp 4, and the telltale-lamp 8 is in a shunt circuit 21 around the lamp 5.

As an example of suitable electric lamps for the purpose in question, the running lights may be 50 volt lamps of 32 candle-power, and the tell-tale lamps may be 125 volt lamps of 2 candle-power each. During the normal operation of the system, the telltale-lamps, owing to their much higher resistance, will permit only a small amount of current to pass through the shunt circuits, this current being sufficient to cause the telltale-lamps to glow dimly without substantial waste of current. In case the dynamo ceases to operate, or the flow of current is interrupted by a break or a cross in the main-circuit conductors, the extinction of the running lights will be indicated by a coincident extinction of the telltale-lamps. In case either running light breaks or burns out, the corresponding telltale-lamp will then receive all of the current in the corresponding circuit, and the resulting increase in its brilliancy will indicate the extinction of the primary light. The same thing will result in the case of a break in the portion of the circuit bridged by any of the shunt-circuits through the telltale-lamps. As a further precaution, in connection with the arrangement just described, the binnacle-lamp 6 may be used as a supplementary telltale device. This lamp is shown as connected in a shunt-circuit 13 which is bridged across a resistance 12 introduced in the main conductor 22. The resistance 12 diverts a sufficient amount of current through the binnacle-lamp to cause the latter to glow normally, but, in case of the extinction of any of the primary lamps, the current through the main conductors is diminished and the

binnacle-lamp then glows less brightly, or becomes dark. This arrangement of the binnacle-lamp does not constitute a part of the present invention, and is not claimed herein.

5 Fig. 3 shows another arrangement of the circuits which differs from that of Fig. 2 in having the primary lights in series in a single circuit, each primary light being in shunt with the corresponding telltale-lamp, 10 as previously described. The several wires in this figure are numbered similarly with the corresponding wires in Fig. 2, the lead wires of the primary lamps 2, 3, 4 and 5 being designated by the reference numbers 14, 15 16, 18 and 20, respectively, while the lead wires of the corresponding telltale-lamps are designated as 15, 17, 19 and 21, respectively. In this figure the binnacle-lamp is 20 also arranged in connection with the telltale in the same manner as in Fig. 2. The operation of the telltale-lamps in this arrangement is substantially the same as in the parallel arrangement of Fig. 2.

While, for the sake of economy, it is preferable to use telltale-lamps of much lower candle-power than the primary lamps, the invention, in its broadest aspects, is not limited to this feature, but resides broadly in the use of a telltale-lamp in shunt with the 30 primary lamp and adapted normally to glow with less than its full rated brilliancy.

What I claim is:

1. The combination of a lighting circuit, comprising a primary incandescent electric lamp, a shunt around said lamp, and a telltale lamp in said shunt having a specific re-

sistance such as to adapt it to burn dimly when the primary lamp is in normal condition.

2. The combination of a lighting circuit, 40 comprising a primary incandescent electric lamp, a shunt around said lamp, and a telltale lamp in said shunt having a lower candle-power and a higher resistance than the primary lamp, whereby the telltale lamp 45 normally will burn dimly but will burn brightly when the primary lamp is extinguished.

3. The combination of a lighting circuit, comprising a primary incandescent electric 50 lamp, a second primary incandescent lamp in series therewith, a telltale incandescent lamp in multiple with the first primary lamp and in series with the second primary lamp, the said telltale being of higher resistance and of lower candle power than said primary lamps, a second telltale incandescent lamp in series with the first primary lamp and in multiple with the second primary lamp, the said second telltale lamp 60 being of higher resistance and of lower candle power than the said primary lamps, whereby the telltale lamps burn dimly when the primary lamps are lit, and when one of the primary lamps burns out, the other is 65 also extinguished and the telltale lamp in multiple with the burned out lamp burns more brightly.

JAMES FRANK KEY,
